UNITED STATES PATENT OFFICE

99,128

DESIGN FOR A STOVE

Bertrand B. Kahn, Cincinnati, Ohio, assignor to
The Estate Stove Company, Hamilton, Ohio, a
corporation of Ohio

Application August 3, 1935, Serial No. 57,929

Term of patent 7 years

To all whom it may concern:

Be it known that I, Bertrand B. Kahn, a citizen of the United States of America, residing at Cincinnati, in the county of Hamilton and State of Ohio, have invented a new, original, and ornamental Design for a Stove, of which the following is the specification, reference being had to the accompanying drawing, forming a part thereof.

The design is illustrated in the accompanying drawing which shows in

Fig. 1 a view in perspective of a stove embodying my new design with the doors thereof closed, the other side of the stove being substantially like the side shown except that it is not provided with ventilating apparatus; and

Fig. 2 a similar view in perspective showing the doors in their open position.

The dominant feature of the design is a gen-

erally symmetrical appearance and arrangement of decorative lines and elements in a stove in which there are two doors of different size and shape, one being larger than the other. The design is applied in a dissimilar manner to each door individually, but in such a way as to carry out a substantially balanced and pleasing and symmetrical arrangement of the stove front as a whole, when the doors are in closed position. The stove is shown as decorated with a pattern including groups of vertically spaced lines applied non-symmetrically to the individual doors, and of a color in pleasing contrast with the remainder of the stove, to provide a symmetrical and pleasing appearance of the stove as a whole.

I claim:

The ornamental design for a stove substantially as shown and described.

BERTRAND B. KAHN.
